US00D965931S

(12) **United States Design Patent** (10) Patent No.: **US D965,931 S**
(45) Date of Patent: **** Oct. 4, 2022**

(54) **PNEUMATIC DUST COLLECTOR**

(71) Applicant: **ATLAS COPCO AIRPOWER,
NAAMLOZE VENNOOTSCHAP,
Wilrijk (BE)**

(72) Inventors: **Prashant K. Rajput**, Maharashtra (IN);
Vishal Krishnarao Patil, Maharashtra (IN);
Vijay Sohanlal Sharma, Maharashtra (IN); **Srinivasan Arjune**, Tamil Nadu (IN)

(73) Assignee: **ATLAS COPCO AIRPOWER,
NAAMLOZE VENNOOTSCHAP,
Wilrijk (BE)**

(**) Term: **15 Years**

(21) Appl. No.: **29/731,300**

(22) Filed: **Apr. 14, 2020**

(30) **Foreign Application Priority Data**

Jan. 28, 2020 (EM) 007565452-0001

(51) LOC (13) Cl. **15-05**

(52) U.S. Cl.

USPC **D32/21; D32/23**

(57) **CLAIM**

The ornamental design for a pneumatic dust collector, as shown and described.

DESCRIPTION

FIG. 1 is a perspective view of the pneumatic dust collector.

FIG. 2 is a front view thereof.

FIG. 3 is a back view thereof.

FIG. 4 is a left side view thereof.

FIG. 5 is a right side view thereof; and,

FIG. 6 is a top view thereof.

1 Claim, 6 Drawing Sheets
